CLAIM

The ornamental design for an apparatus for advancing axially aligned pipes telescopically into or out of engagement, as shown and described.

DESCRIPTION

FIG. 1 is perspective view of the apparatus for advancing axially aligned pipes telescopically into or out of engagement showing my new design;

FIG. 2 is a top plan view thereof without the ratchet handle; FIG. 3 is a front view thereof without the ratchet handle, the rear view being a mirror image thereof;

FIG. 4 is a right end view thereof;

FIG. 5 is a left end view thereof;

FIG. 6 is a bottom view thereof; and,

FIG. 7 is a front view with the ratchet handle.

The ratchet handles have not been shown in figure drawings 2-6 for ease of illustration.
